United States Patent Office

Des. 203,200

Patented Dec. 14, 1965

203,200

SERVING CART

Bert J. Klein and Andre Bus, Altavista, and John B. Thorn, Lynchburg, Va.

Filed Apr. 19, 1965, Ser. No. 84,862

Term of patent 14 years

(Cl. D33—14)

The single figure is a perspective view of a serving cart embodying our new design.

The end of the article not shown is like the end shown while the back of the article is plain and unornamented. The upper rear portion of the top section of the article is like the corresponding portion of the front.

We claim:

The ornamental design for a serving cart, as shown and described.
